UNITED STATES PATENT OFFICE.

CHARLES N. NEWCOMB, OF WEST PALM BEACH, FLORIDA.

SUCTION-DREDGE.

No. 887,506.

Specification of Letters Patent.

Patented May 12, 1908.

Application filed October 19, 1907. Serial No. 398,218.

To all whom it may concern:

Be it known that I, CHARLES N. NEWCOMB, a citizen of the United States, residing at West Palm Beach, in the county of Dade and State of Florida, have invented new and useful Improvements in Suction-Dredges, of which the following is a specification.

This invention relates to suction dredges, the object of the invention being to simplify and improve the general construction of suction dredges, whereby they are rendered more reliable in operation, less liable to get out of order and capable of being more easily manipulated.

One of the main objects of the present invention is to provide in connection with that element which scoops up the sand, mud or other material, means for supplying water thereto in such manner as to dislodge such material from the scoop and insure the delivery thereof to the suction pipe.

With the above and other objects in view, the nature of which will more fully appear as the description proceeds, the invention consists in the novel construction, combination and arrangement of parts hereinafter fully described, illustrated and claimed.

In the accompanying drawings, Figure 1 is a plan view of the dredging apparatus 30 mounted on a barge. Fig. 2 is an enlarged plan view of the hollow rotary head or scoop element of the mechanism. Fig. 3 is a side elevation of the suction pipe. Fig. 4 is a vertical longitudinal section through the top portion of the apparatus showing the parts adjacent thereto and a portion of the driving mechanism. Fig. 5 is an elevation of the gear case and attached parts, showing the suction pipe in section. Fig. 6 is a plan view of the head of the suction pipe. Fig. 7 is a similar view of the head of the hollow rotary head or suction element.

Referring to the drawings, and particularly to Fig. 4, the apparatus contemplated in this invention comprises essentially an inner tube or suction pipe section 1, which constitutes a portion of the suction pipe of the apparatus, while 2 designates the dredging element which is in the form of a hollow 50 rotary head surrounding and revolving around the suction pipe section 1.

The suction pipe section 1 is non-rotatable and is preferably coupled by a flexible section 3 to the suction pipe 4 which leads to a 55 suction pipe section 5 of suitable construction; said pipe communicating with the dis-

charge pipe 6, the last named parts being indicated by dotted lines in Fig. 1.

The suction pipe 1 is closed at its outer end by a head 7 having an inwardly offset hollow 60 boss 8 which is threaded to receive a grease cup 9 adapted to contain a suitable supply of lubricating material which feeds through openings 10 in the boss 8 to the bearing between the pipe 1 and head 2. The member 65 2 is closed at its outer end by a head 11 which is provided with a journal portion 12 which works within the hollow boss 8 of the pipe 1, as shown in Fig. 4, the two heads 7 and 11 being connected by a bolt 13. The 70 outer end or head of the bolt 13 is covered by a protecting cap 14, and by reason of the construction just herein above described all foreign matter is excluded from the bearing 75 between the pipe 1 and head 2.

The pipe 1 is provided with an elongated opening 15 which gradually tapers from end to end, the smaller end being forward while the larger end is toward the outer end of the pipe where the greatest amount of material 80 is taken in, it being understood that the sand, mud and other material all passes inward within the opening 15. The head 2 is provided with one or more spiral series of openings 16, each of which is partially covered by 85 a scoop or bucket 17 open at the front and back and connected at its opposite ends to the outer surface of the head 2 as shown at 18. Each bucket or scoop is preferably formed of sheet metal and the main body 90 thereof is transversely inclined with respect to the outer surface of the head so as to provide a relatively large scoop orifice 19 at the front in which the material is received, and the relatively smaller water inlet passage 20 95 which in the rotation of the head is at the rear of the scoop or bucket. The forward edge of the scoop shaves the sand or mud and gathers the same into the scoop while water enters the rear orifice 20 and dislodges 100 such material from the outer wall of the scoop, so that it is readily sucked inward through the opening 16 and carried inward through the opening 15 in the pipe by suction when the bucket or scoop comes opposite 105 such opening 15. The feature just named has been found in practice to be a most valuable one, as it prevents congestion of material in the scoops or buckets and greatly facilitates the operation of the machine as a 110

Secured to the inner end of the head 2 is a

sprocket wheel 21 having a laterally projecting rim 22 on which the sprocket teeth are located. Working inside of the flange or rim 22 is a circular series of anti-friction rollers 23 which work upon a wear band 24 surrounding and secured to the suction pipe 1, a roller bearing being thus formed between the sprocket wheel and the pipe 1 which permits the head 2 to revolve freely and with a minimum amount of friction around the pipe 1. Coöperating with the sprocket wheel 21 is a sprocket chain 25 which derives its motion from a sprocket pinion 26 fast on a motor shaft 27 extending in a plane parallel to the pipe 1. The shaft 27 is driven by a motor or small engine 28, the bed or base of which is provided with good strong trunnions 29 journaled in suitable bearings on the barge, as shown in Fig. 1, and by means of this construction, the engine or motor 28 is tilted together with the pipe 1 and shaft 27, the operative relation of which is maintained at all times.

The sprocket wheels and chain above described are inclosed in a gear case embodying oppositely arranged plates 30 and 31, the plate 30 having a central opening in which the rotary head turns, while the other plate 31 is permanently secured to a flanged collar 32 fast on and surrounding the pipe 1.

33 designates a spacing rim in the form of an annular band which is interposed between the outer end portions of the plates 30 and 31 and securely held in place by bolts 34 or their equivalent, thus forming a tight gear case in which the sprocket driving mechanism for the rotary head 2 is inclosed.

Secured to the plate 31 of the gear case is a bearing bracket 35 provided with suitable reinforcing flanges 36 and 37 and also provided with slots 38 to receive the securing bolts by which the bracket is fastened to the gear case, thus permitting said brackets to be adjusted vertically to give the proper tension to the sprocket chain 25. The bearing bracket 35 also embodies a movable cap piece 39 to admit of the removal of the motor shaft 27 when necessary.

The flanged collar 32 is provided at opposite sides with lugs 40 to which are secured the outer ends of a pair of inwardly diverging braces 41 secured at suitable points as at 42 to the barge, which braces act to stay and keep in position the outer end of the pipe 1, while in operation, while permitting said pipe to rise and fall during the dredging operation. The brace rods 41 are preferably provided with turn buckles 43 so that they may be kept under the proper tension.

Having thus fully described the invention, what is claimed as new is:—

1. A suction dredge comprising a suction pipe section in communication with the suction pipe and provided with a single opening, and a rotary head revolving around said pipe

and concentric therewith and embodying a series of inlet openings arranged to successively register with the opening in the suction pipe section.

2. A suction dredge embodying a suction pipe section, in communication with the suction pipe and provided with an opening therein, and a rotary head revolving around said pipe and embodying a series of spirally arranged inlet openings adapted to be successively brought into line with the opening in the suction pipe section. 75

3. A suction dredge embodying a suction pipe section in communication with the suction pipe and provided with an elongated opening wider at its outer end than at its inner end and a rotary head revolving around said pipe and comprising a series of inlet openings adapted to successively register with the opening in the suction pipe section. 80

4. A suction dredge embodying a suction pipe section, in communication with the suction pipe and provided with an elongated opening extending lengthwise thereof and gradually increasing in width toward one end, and a rotary head revolving around said pipe and comprising a plurality of inlet openings adapted to successively register with the opening in the suction pipe section. 85

5. A suction dredge embodying a suction pipe section in communication with the suction pipe and provided with an inlet opening, a rotary head revolving around said pipe and comprising a plurality of inlet openings adapted to register with the inlet opening of the pipe, and scoops or buckets arranged adjacent to said openings in the rotary head, each of said scoops providing a scooping aperture for the inlet of the material dredged, and an independent water inlet orifice, substantially as described. 95

6. A suction dredge embodying a suction pipe section, in communication with the suction pipe and provided with an inlet opening, a rotary head revolving around said pipe and embodying a plurality of inlet openings adapted to register with the inlet opening of the pipe, and scoops or buckets arranged adjacent to said openings in the rotary head, each of said buckets being open at the front side to receive the dredged material and also provided at the rear side with a water inlet orifice. 110

7. A suction dredge embodying a suction pipe section, in communication with the suction pipe and provided with an inlet opening extending lengthwise thereof and increasing in width toward the outer end of the pipe, and a rotary head revolving around said pipe and comprising a plurality of inlet openings adapted to register with the inlet opening of the suction pipe section. 115

8. A suction dredge embodying a suction pipe section, in communication with the suction pipe and provided with an inlet opening, 120

- a rotary head concentric with and revolving around said pipe and provided with inlet openings adapted to register with the inlet openings of the pipe, a gear wheel encircling 5 said head and fast thereon, a motor shaft extending parallel with said rotary head and geared to the wheel on the rotary head for imparting motion to the latter, and a motor for driving said shaft.
- 10 9. A suction dredge embodying a suction pipe section, in communication with the suction pipe and provided with an inlet opening, a rotary head revolving around said pipe and provided with inlet openings which register 15 with the inlet opening of the pipe, and a motor mounted in fixed relation to the suction pipe, adapted to swing therewith and geared to the rotary head for driving the latter, substantially as described.
- 20 10. A suction dredge embodying a suction pipe section, in communication with the suction pipe and provided with an inlet opening, a rotary head revolving around said pipe and provided with a series of inlet openings which 25 register with the inlet opening of the pipe, a sprocket wheel fast to the rotary head and
- encircling the pipe, a countershaft extending parallel to the pipe, a sprocket wheel thereon, and a chain connecting said sprocket wheel and the sprocket wheel on the rotary 30 head, and means for actuating said countershaft.
11. A suction dredge embodying a suction pipe section, in communication with the suction pipe and provided with an inlet opening, 35 a rotary head revolving around said pipe and provided with inlet openings which register with the inlet opening of the pipe, and a motor operatively geared to said head for imparting motion to the latter, the said motor 40 and pipe being supported upon trunnions so that in the swinging movement of the head and parts carried thereby the motor will swing correspondingly thereby maintaining the operative relation between the motor and 45 the parts driven thereby.

In testimony whereof I affix my signature in presence of two witnesses.
